A. E. OSTRANDER.

BRAKE STEP.

APPLICATION FILED NOV. 12, 1913.

1,097,931.

Patented May 26, 1914.

UNITED STATES PATENT OFFICE.

ALLEN EDWARD OSTRANDER, OF RIDGEWOOD, NEW JERSEY.

BRAKE-STEP.

1,097,931.

Specification of Letters Patent.

Patented May 26, 1914.

Application filed November 12, 1913. Serial No. 800,603.

To all whom it may concern:

Be it known that I, ALLEN E. OSTRANDER, residing at Ridgewood, Bergen county, New Jersey, and being a citizen of the United

5 States, have invented certain new and useful Improvements in Brake-Steps, of which the following is a full, clear, and exact description, such as will enable others skilled in the art to which it appertains to make 10 and to use the same, reference being had to the accompanying drawings, which illustrate the preferred form of the prevention, though it is to be understood that the invention is not limited to the exact details 15 of construction shown and described, as it is obvious that various modifications thereof will occur to persons skilled in the art.

In said drawings Figure 1 is a plan view of the brake step, shown as attached to the 20 end sheet of a steel car. Fig. 2 is a front elevation of the same, a portion of the brake step being broken away to more clearly show the brake mast pawl plate applied. Fig. 3 is an end elevation of the 25 brake step attached to the car end sheet. Fig. 4 is a vertical section through one of the side binding strips taken on the line 4-4 of Fig. 2; and Fig. 5 is a vertical section through one of the end binding 30 strips taken on the line 5-5 of Fig. 1.

This invention relates to brake steps such as are applied to the end of railway cars, and upon which the brakeman stands when operating the brake hand wheel.

35 It has for its object a construction which shall be strong and at the same time simple, the latter feature resulting in a comparatively low manufacturing cost.

The step is designed so that it may be 40 applied advantageously in accordance with the location of the brake mast, which is not always in the same position on different cars, said step being reversible in more than one direction.

45 Another object is to create greater safety to the person standing upon the brake step, and this is accomplished by the use of expanded metal which constitutes the major part of said step, and is bound with and 50 inclosed by suitable binding strips. Slippery conditions in inclement weather, which are present in the wooden and cast metal steps of former and present practice, are eliminated in the brake step disclosed herein. Moreover, the soles of the shoes of the

brakeman may be freed from caked snow, clinging thereto, by the upper ridges of the expanded metal, greatly increasing his safety.

In the drawings, the usual brake step 80 brackets A, riveted or otherwise secured to the end sheet B of a car body, form the supporting means for the brake step. The ends of the expanded metal tread 1 rest upon the tops of brackets A and are clamped 85 between them and the end binding strips 2 by means of rivets 3 which pass through said end binding strips, the end rhombic interstices of the tread at the vertices of the outer acute angles, and the brake step 70 brackets. The sides of the tread 1 are bound within the side binding strips 4 of sheet metal, the latter being bent to form a relatively T-shaped cross section, the internal surfaces of said side binding strips being 75 spaced apart, and the space between the horizontal flanges permitting the insertion of the sides of the expanded metal tread. Through the top horizontal flanges of the side binding strips 4, the outer rhombic interstices of the tread 1 at the vertices of the outer obtuse angles of the same, and the bottom or lower horizontal flanges of said side binding strips, pass rivets 5, locking and clamping the sides of the tread 1 within 80 the side binding strips 4, and stiffening it 85 against flexure. At their ends, the side binding strips are shown as indented or compressed to adjust them to the upper bearing surfaces of the brake step brackets 90 A employed to support said brake step. Figs. 2 and 3 best disclose this feature. The upper bearing surfaces of the brake step brackets are shown in Fig. 3 as being bent 95 into more than one plane, in order to follow the uneven surface presented by the under-side of the bottom horizontal flanges of the side binding strips and the bottom of the tread 1. The end lapping portions of the end binding and side binding strips, 2 and 100 4, respectively, are secured together by rivets 6, and form a strong and rigid frame for supporting the expanded metal tread 1, restraining it against such stresses as may be set up therein when it is sustaining a 105 person.

Brake masts being differently situated on various cars, it becomes necessary to so apply the brake step in any case that it will not be interfered with, as, say, by an end stake, 110

ladder rounds, etc. Hence, the brake step is designed to be turned when desired to cause that portion of its length which projects a greater distance from the brake mast to extend away from the obstruction. Again, certain brake masts are somewhat farther removed from the car end than others, requiring a corresponding change in the transverse location of the opening in the 10 brake step for the brake mast. At a point that is situated on neither the longitudinal nor transverse median line of the brake step, the lattice work of the tread 1 is cut away, as at 7, for the passage of the brake 15 mast C, which carries the usual brake ratchet wheel D. Because of its location in the tread 1 the opening for the brake mast, shown at 7, may occupy the position illustrated in the drawings, or, upon turning 20 said brake step upside down, the revolution being made in the direction of its length, it will be at the right hand end of said step. If the brake mast on any car is farther 25 removed outwardly from the car end, inverting the brake step in the direction of its width will carry the opening for the 30 brake mast farther out from the car end. And, revolving said brake step in a horizontal plane, so that the inside becomes the outside, the opening at 7 will be changed 35 from a left hand position to a right hand one, and will also be farther removed outwardly from the car end. As a consequence, it is possible to keep a large stock of the 40 brake steps on hand, to be drawn from for various cars as occasion demands. It is preferable that the brake mast pawl plate 8 be not attached to the tread 1 until the brake step is applied to the car when it may be positioned as will be required for the particular car to be equipped.

The brake mast pawl plate is provided on its underside with circular bosses 9, shown in Figs. 1 and 2, of substantially the same 45 altitude as the thickness of the expanded metal tread 1, and they are spaced apart so as to reside in certain of the interstices of said tread. Through the brake mast pawl plate 8 and its bosses 9 pass rivets 10, which 50 continue through tie plate 11, beneath the tread 1, whereby the brake mast pawl plate is securely clamped to the tread.

The brake mast pawl plate is provided with an integral stud 12, which carries a 55 brake pawl E for engaging the brake ratchet wheel D in the usual manner, the latter being maintained in place by the horizontal flange of a semi-circular brake ratchet wheel retaining wall 14. It will be observed that 60 the brake ratchet wheel cannot be dislodged except after the brake mast has been withdrawn, and that the hole 15 in the tie plate 11 serves as a guide for the brake mast C which passes through it.

The brake step as a whole is inexpensive,

strongly constructed, adapted to meet varying conditions, and because of its adaptability to almost any car in service, may be carried in stock in large quantities. As pointed out hereinbefore, it sheds the rain and snow, dislodges dangerous snow cakes from the feet of those using it, and its grated surface is adapted to give an unusually good foothold. Through its brake mast pawl plate and its tie plate the brake 70 step guides and steadies the brake mast insuring proper relationship of the brake pawl and brake ratchet wheel at all times, and in this the bosses on the underside of the 75 brake mast pawl plate assist.

What I claim is:—

1. In a reversible brake step for cars, a frame comprising sheet metal side binding strips having upwardly and downwardly extending vertical flanges, metal strip end binding strips, brackets co-acting therewith, an expanded metal tread outlined by said frame, and having its mesh interrupted for the passage of a brake mast, and means for securing the parts together. 80

2. In a reversible brake step for cars, an expanded metal tread, a frame comprising sheet metal edge binding strips flanged to extend perpendicularly above and below said tread, brackets co-acting therewith, 85 said frame outlining and embracing said expanded metal tread and the mesh of said tread being cut away for the passage of a brake mast. 90

3. In a reversible brake step for cars, an expanded metal tread the mesh of which is cut away to accommodate a brake mast, an inclosing frame comprising sheet metal side binding strips pressed to form a T-shaped cross section, symmetrically disposed above and below said tread, substantially straight metal strap binding ends, and supporting brackets co-acting therewith. 100

4. In a reversible brake step for cars, an expanded metal tread cut away to accommodate a brake mast at a point that is away from the longitudinal and transverse median lines of the brake step, whereby varying dispositions of the mast of the step may be made when the step is reversed and a tread inclosing frame comprising metal binding strips pressed to extend materially above and below said tread. 110

5. In a reversible brake step for cars, an expanded metal tread cut away for a brake mast at a point located on neither the longitudinal nor transverse median line of said step, a brake mast pawl plate having depending bosses adapted to be positioned within certain of the interstices of the tread, 120 a tie plate riveted thereto, and a frame inclosing said tread, said frame comprising pressed metal binding strips of substantially a horizontally disposed T-shaped cross section. 125

6. In a reversible brake step for cars, an expanded metal tread cut away at a point located at one side of the longitudinal and transverse median lines of the tread, pressed sheet metal side binding strips having a cross section shaped substantially like a horizontally disposed hollow T symmetrically disposed above and below the tread, supporting brackets, a brake mast pawl plate 10 with depending bosses adapted to occupy certain interstices of the tread, and a tie plate riveted thereto to lock the same in position on the tread.
7. In a reversible brake step for cars, an expanded metal tread, the mesh of which is interrupted at a predetermined location to accommodate a brake mast to be projected through said interrupted tread portion, said interrupted portion being located at one side 15 of the longitudinal and transverse median lines of the tread, whereby the location of the brake mast opening is made changeable, and means for supporting said tread.
8. In a brake step for cars, an expanded metal tread the mesh of which is interrupted at a predetermined location to accommodate a brake mast to be projected through said interrupted tread portion, said interrupted portion being located at one side of the longitudinal and transverse median lines of the tread whereby the step is made reversible for the purpose set forth, in combination with sheet metal side binding strips of T -shaped cross-section, strip metal end binding strips lapping said side binding strips and being connected together at each point 20 of lapping, and means connecting said strips to said expanded tread.
9. In a brake step for cars, an expanded metal tread the mesh of which is interrupted at a given location to accommodate a brake mast to be projected through said interrupted tread portion, said interrupted portion being located at one side of the longitudinal and transverse median lines of said 25 tread, a brake mast pawl plate comprising depending bosses adapted to be positioned within certain interstices of the tread, an integral stud for a brake pawl, and a flanged semi-circular integral wall for normally retaining a brake ratchet wheel in place.
10. In a brake step for cars, an expanded metal tread the mesh of which is interrupted at a given location to accommodate a brake 30 mast, a brake mast pawl plate having a brake mast opening therein, said pawl plate comprising depending bosses adapted to be positioned within certain interstices of said tread, an integral brake pawl supporting 35 stud, and an integral flanged semi-circular ratchet wheel retaining wall, and a tie plate, with a guiding opening for the brake mast, secured to said pawl plate, said tread being interposed between said pawl plate and said 40 tie plate.

In witness whereof I have hereunto set my hand in the presence of two witnesses.

ALLEN EDWARD OSTRANDER.
